US0D1008613S

(12) **United States Design Patent** (10) **Patent No.:** **US D1,008,613 S**
(45) **Date of Patent:** **** Dec. 26, 2023**

(54) **SANDAL**

(71) Applicant: **Fangping Li**, Sanming (CN)
(72) Inventor: **Mingjie Ding**, Quanzhou (CN)
(**) Term: **15 Years**
(21) Appl. No.: **29/869,363**
(22) Filed: **Dec. 29, 2022**

(51) **LOC (14) Cl.** **02-04**
(52) **U.S. Cl.** **D2/916**
USPC **D2/916**

(57) **CLAIM**

The ornamental design for a sandal, as shown and described.

DESCRIPTION

FIG. 1 is a top perspective view of a sandal, showing my new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a rear view thereof; and,

FIG. 9 is an enlarged perspective view of detail "9" identified in FIG. 1.

The dash dot dash lines in FIGS. 1 and 9 are for the purpose of illustrating the enlarged view indicators and form no part of the claimed design.

1 Claim, 9 Drawing Sheets
